TRIP LOCK

Herbert W. Neunherz, Gardner, Mass.

Application April 24, 1941, Serial No. 390,153

11 Claims.

(Cl. 292—4)

This invention relates to trip locks in general and more particularly as herein illustrated the invention is applied as a locking medium for the drop side of an infant's crib.

Objects of the invention include the provision of a trip lock mechanism for the drop side of an infant's crib which is simple in construction, positive in operation, and very easy of access; the provision of a pair of axially and rotatably movable locking elements which are rotated by an easily accessible trip lever and during which movement are axially movable by means of stationary cams to be retracted from notches in the drop side guide rods; and the provision of a trip lock as above described which may be easily actuated by the knee of the operator to unlock the drop side from its guides, and which is provided with spring means to automatically extend the locking means into locking engagement with the guides upon removal of pressure from the trip lever.

Other objects and advantages of the invention will appear hereinafter.

Reference is to be had to the accompanying drawing, in which

Fig. 1 is a rear view of a preferred embodiment of the invention showing the same in its relation to the crib, parts of which are broken away;

Fig. 2 is an enlarged rear view of the trip parts shown in Fig. 1, parts being broken away and showing the mechanism in unlocked condition;

Fig. 3 is a cross section on the line 3—3 of Fig. 2;

Fig. 4 is a plan view of the cams and associated parts showing a modification;

Fig. 5 is a front view of the invention according to the modification of Fig. 4; and

Fig. 6 is a cross sectional view similar to Fig. 3, but showing a modification of the trip lever.

Referring to Fig. 1, the front crib posts are indicated at 10, these posts being provided with lower angle brackets 12 which retain the lower ends of the drop side guides 14. These guides are secured to the crib posts at their upper ends by means of bolts 16, as shown. The guides are each provided with a pair of locking notches as at 18.

The bottom rod of the drop side is shown at 20 and it will be understood that this drop side per se will be substantially the same as the conventional crib drop side with an upper bar and connecting spindles not here shown. The bar 20 is apertured adjacent each end to be slidably received on the guides 14, as is indicated at 22. Inwardly from these apertures a pair of brackets 24 are secured to the bottom side of the bar 20 by screws or other convenient means. Brackets 24 are each provided with a pair of down-turned apertured ears 26 through which rods 28 slidably

extend. The rods 28 are arranged in the ears 26 to lie beneath and parallel with bar 20. As shown in the drawing, the rods 28 terminate at their adjacent ends in down-turned ends or angles 30 and are square cut at their opposite ends for entrance into the notches 18. It will be seen from the above that the drop side will be held in elevated position when the rods 28 hold the same in location as shown in Fig. 1, but when the rods are released from the upper notches 18, the drop side will descend by gravity to its lowermost position, thus exposing one side of the crib.

Spaced from the down-turned ends 30, rods 28 are provided with swaged portions or other stopping means 32. A trip lever 34 having right angled ears 36 is suspended from the rods so as to pivot thereon, and the ears 36 together with portions 32 provide abutment means for the ends of compression springs 38. The downturned ends of rods 28 ordinarily will lie in vertical position abutting the rear surface of trip lever 34 such that when the lever 34 is swung clockwise about rods 28 as a pivot, it obviously contacts the down-turned ends 30 and thus turns the rods 28 a partial revolution. It will be observed that springs 38 constantly urge the rods 28 to locking position in notches 18, but when the rods are retracted from the notches they may ride on the inner surfaces of the guide rods 14 and there will be no locking action even though pressure is released from lever 34.

A U-shaped bracket 40 is attached to the bar 20 so that the legs of the U straddle the lower edge of the bar and the latter is spaced from the connection between the legs, see Fig. 3. The bracket 40 is provided with a cut-out slot 42. This slot is in the form of a trapezoid and its longer edge 44 lies on the curve of the bracket more closely adjacent to one leg than the other, as will be clear from a comparison of Figs. 3 and 4. The converging sides 46 of the trapezoid extend along the curve of the bracket 40 between its legs and terminate on one leg closely adjacent to the rear edge of the bottom of the bar 20. The down-turned ends or angles 30 are arranged to lie in the slot 42 and obviously spring 38 forces these ends to bear against the converging sides 46 at all times. The sides 46 are essentially cam surfaces as will be later described. Bracket 40 is provided with integral pieces 47 for the purpose of providing bearings for rods 28 so as to support the latter.

As shown in Fig. 4, the springs 38 may be dispensed with and a single U spring 48 which bears outwardly against the down-turned ends 30 and has a coil supported on a hook 50 on the bracket 34 may be used instead of spring 38, and as shown in Fig. 5, the rods 28 may be recessed 60 into the bottom of the bar 20 to be there sup-

ported by ears 26' which extend oppositely to ears 26. A further change may be made, as shown in Fig. 6, wherein the lever 34 is bent outwardly beyond the vertical face of the drop side so that the same may be more easily actuated by the knee of the operator, and bracket 34 may be provided with an upstanding lug 52 to act as a stop against the edge 44 of the slot 42 so that the lever may not travel any further in a counterclockwise direction than as shown in Fig. 6.

The device operates as follows: With the parts as shown at rest in Fig. 1, the springs 38 provide means whereby the straight ends of rods 28 are located in the upper notches 18, and it being desired to lower the drop side to which the lock is connected, as shown, the trip lever 34 is moved by the hand or knee of the operator in a clockwise direction, see Fig. 3, so that the same would be pivoted towards the observer in Fig. 1. The trip lever 34 abutting the down-turned ends 30 of the rods 28 will clearly turn the same for a partial rotation about the rods 28 as an axis. However, since the springs continuously urge the rods 28 outwardly and since the down-turned ends 30 thus constantly engage the converging edges 46 of bracket 40, the ends 30 will be forced towards each other as shown in Fig. 2 as the lever is swung clockwise in Fig. 3. The down-turned ends 30 thus in effect ride up the surfaces 46 and thus approach each other, drawing rods 28 out of the notches 18. As soon as the rods 28 are free of notches 18, the drop side will start to descend by gravity and pressure may be released from lever 34 since the rods 28 will ride on the inner surface of the guides 14 as shown in Fig. 2. When the drop side is low enough, springs 38 will automatically urge rods 28 into engagement with the lower notches 18 and thus the drop side will be locked in lowermost position.

This invention has been illustrated as applied to an article of furniture such as a drop side of a crib, but it is contemplated that the same structure may be used to lock any two relatively movable members such as doors, windows, etc.

Having thus described my invention and the advantages thereof, I do not wish to be limited to the details herein disclosed, otherwise than as set forth in the claims, but what I claim is:

1. In a device of the class described, a pair of relatively movable elements, means to lock said elements together including a depression on one element and a rod slidable into and out of said depression and located on the other element, resilient means to urge said rod towards depression-entering position, and means to withdraw said rod from such position, said last mentioned means comprising a cam, a projection on said rod engaging said cam, a separate lever engaging said projection and adapted to rotate the same against the cam, the latter being effective to force said rod away from the depression upon actuation of said lever.

2. A device as recited in claim 1, in which the resilient means is effective to hold the projection against the cam.

3. In a device of the class described, two relatively slidable elements, a notch in one element and a rod on the other element slidable into and out of engagement with said notch, means to

continually urge said rod towards the notch, and means to selectively retract the rod, said means comprising a fixed bracket having a surface inclined with respect to said rod, a part of said rod engaging said surface, and a separate pivoted lever adapted to engage said part to turn the rod so as to slide said part on said surface away from said notch.

4. In a device of the class described, a support, a U-shaped bracket depending therefrom, a rod journaled in said bracket and having an angular projection, a cam on said bracket extending from between its legs angularly partly across one leg in a direction away from said rod, means continually urging said projection against said cam, and means to slide said projection over said cam to thereby move said rod in a direction against the action of said urging means.

5. In a device of the class described, a support, 20 a bracket thereon, a slot in said bracket having closed ends and converging sides, a pair of rods extending into said bracket and having angles thereon hooked into the slot so that said angles engage opposite converging sides of said slot, 25 spring means urging said rods in a direction to hold said angles against the slot sides, and means to partially rotate said rods, whereby said angles are normally located at the wider end of the slot and are movable by said last named means towards the narrower end of the slot to draw said angles toward each other.

6. In a device of the class described, a bracket having parallel legs and an arcuate connection therebetween, a slot in said bracket located substantially in said arcuate connection, said slot having converging sides extending toward one of said legs, a pair of aligned rods having bent ends located in said slot, spring means to urge said rods apart and the bent ends against said converging sides, a lever pivoted on said rods and effective to rotate said rods by engagement with said bent ends, whereby the latter will ride up on the converging sides of the slot and thus be forced towards each other.

7. In a device of the class described, a bracket of general U-shape having a slot therein extending along the closed end of the U, said slot having converging sides and closed ends, a pair of rotatable rods having bent ends located in the slot, means to yieldingly hold each bent end in contact with a separate converging side of the slot so that bent ends normally rest adjacent the wider end of the slot, and manual means to rotate said rods so that said bent ends travel along said slot sides and approach each other, whereby said rods are drawn toward each other.

8. A device as recited in claim 7 wherein said yielding holding means tends to return said bent ends and said manual means to a position of rest with said bent ends adjacent the wider end of the slot.

9. A device as recited in claim 7 wherein said manual means comprises a lever engaging said bent ends.

10. A device as recited in claim 7 wherein said manual means comprises a lever pivoted on said rods.

11. A device as recited in claim 7 wherein said manual means comprises a lever, there being a stop thereon for engagement with said bracket.

HERBERT W. NEUNHERZ.
